UNITED STATES PATENT OFFICE.

EDGAR E. PHINNEY, OF NEW YORK, N. Y., ASSIGNOR TO MONROE CALCULATING MACHINE COMPANY, OF NEW YORK, N. Y., A CORPORATION OF NEW YORK.

CARRYING MECHANISM FOR CALCULATING-MACHINES.

1,354,841.

Specification of Letters Patent.

Patented Oct. 5, 1920.

Original application filed January 13, 1917, Serial No. 142,190. Divided and this application filed October 16, 1918. Serial No. 258,419.

To all whom it may concern:

Be it known that I, EDGAR E. PHINNEY, a citizen of the United States, resident of New York, in the county of New York and 5 State of New York, have made a certain new and useful Invention in Carrying Mechanism for Calculating-Machines; and I declare the following to be a full, clear, and exact description of the same, such as 10 will enable others skilled in the art to which it appertains to make and use the invention, reference being had to the accompanying drawings, and to letters or figures of reference marked thereon, which form a part of 15 this specification.

Figure 1 is a plan view of the registering wheels and of the carrying dogs or pawls, parts being broken away.

Fig. 2 is a section on the line 2—2, Fig. 1. 20 Fig. 3 is a similar view, showing a carrying member thrown by rotation of a registering wheel, and the carrying shaft moved toward the intermediate gears and rotated one half around.

Fig. 4 is a section on the line 4—4, Fig. 1. 25 Fig. 5 is a detail face view of the cam member of the means for locking the carrying collars with their teeth in spiral relation.

Fig. 6 is an edge view of the same.

Fig. 7 is a detail edge view of the lever member of said locking means.

Fig. 8 is a detail face view of the same.

Fig. 9 is a section on the line 9—9, Fig. 10. 35 Fig. 10 is a detail end view of the carrying shaft and the members carried thereby.

Fig. 11 comprises right-angular sectional views of a collar 42, showing the mounting therein of a carrying tooth and its 40 spring.

The invention has relation to carrying mechanism for calculating machines of the type operable forwardly and reversely, according to the nature of the problem, and 45 employing a series of carrying members spirally arranged about a shaft; the object being to provide improved means for rearranging said members in a reverse spiral upon reverse operation of said machine, to 50 obtain under all conditions a successive carrying action, from the lower to the higher order indicators of the machine. The particular objects and advantages of the invention will hereinafter appear.

The carrying mechanism is shown as applied to the machine of my co-pending application for patent Serial No. 142,190, filed January 13, 1917, of which this is a divisional application, and reference is made thereto for such parts of the complete device as are non-essential to the present combination. 55

The invention consists in the novel construction and combinations of parts, as hereinafter set forth. 65

In the accompanying drawings, illustrating the invention, the numeral 4 designates the transversely shiftable carriage of a calculating machine, wherein are mounted, upon shaft 6, the wheels 5, whereon are registered the figures previously set up upon the keyboard of the machine. The registering wheels 5 are actuated, in the registering and carrying operations, through the medium of intermediate gears 11, mounted 70 upon shaft 12, toward and away from which gears the carrying shaft is rocked, as described in my hereinbefore mentioned application No. 142,190. 75

The carrying shaft 9 is provided with a 80 series of annular collars 42, each collar having guides 43 wherein works a transversely slid able dog or tooth 8, and having also a transversely extending pin 45, working in a slot 46 of the collar next adjacent thereto at one side, the collar 42^a at one end of the series being fast to the shaft and all of the other collars having usually a frictional bind upon the shaft, to rotate therewith, but admitting of a movement of the 85 collars with respect to the shaft against such frictional bind or resistance. The fast end collar and all of the other collars have each a pin and slot, as stated, and a member c, herein after described, at the end of 90 the series opposite the fast end collar, has a pin 45^a only, and no slot and no dog or tooth. The dogs of all of the collars are arranged spirally, entirely around the shaft in a single series. 95

Located between the intermediate gears 11 are reciprocatory carrying members 47, pivoted at 48 and having each an arm 49, normally extending in the path of a transverse pin 50 of a registering wheel 5, each registering wheel having a pin 50, and said member having an oppositely projecting arm 51, provided with a cam surface 52, adapted to 100 105

extend within the path of movement of a carrying dog, there being one member 47 for each dog and for each registering wheel.

The cams 52 of the arms 51 are each 5 double, having two inclined cam surfaces, one of which acts upon the dogs to move them endwise in the rotation of the carrying shaft clockwise, and the other oppositely inclined part acting to move the dog endwise 10 in the reverse spiral arrangement, the dogs moving endwise in the same direction into active position, or alinement with the gears 11, in each case. The dogs are returned to normal position by springs 53 thereof (bearing 15 at their left-hand ends, Fig. 1 against shoulders of the collars), and the pivoted carrying members are returned to normal position by radial projections or fingers 54 of the carrying shaft, said fingers following 20 the dogs and having end cam surfaces 55, engaging said members, the cams 55 being double, having oppositely inclined parts, to return said members in either direction of rotation.

25 The radial fingers 54 are loosely mounted upon the carrying shaft, between the collars therecf, each finger having a connection with the end of a pin 45 of the second collar therefrom at one side thereof, and being 30 movable with said pin and collar, in the rearrangement to reverse spiral of the carrying dogs, to position at the opposite side of the carrying dog of the adjacent collar at this side. The fingers, being moved to the 35 opposite sides of the carrying dogs, are in position to return the carrying members 47 to normal position after said members have acted upon said dogs upon reverse movement of the carrying shaft.

40 Located between the intermediate gears are collars 56, carrying each a spring-pressed pin 57, said pin engaging either of two recesses 58 of the pivoted carrying members, to retain them in normal position 45 and in position when thrown pivotally.

Means are provided to check the movement of the pin 45^a with the shaft 9 while the rearrangement of the carrying teeth to reverse spiral is being effected, and embodying 50 also means for positively locking the series of collars, with the teeth thereof in spiral arrangement, including preferably a member *a*, fast upon the shaft and having a circumferential notch *b*; a cam member *c*, 55 loosely mounted upon the shaft and having a peripheral cut-away or reduced portion *d*, and a lever member *e*, also loosely mounted upon the shaft and the body *e'* of which is of a radius less than that of the body of 60 said cam member, said lever member being provided with a radial extension *f*, having at its outer end a laterally offset head *g*, overlying the reduced portion of the cam member and having its outer surface lying 65 within or registering with a circle inscribed

with the shaft as a center and a radius equal to the longer radius of the body of the cam member, said lever member having at one side a circumferential notch *h*, and at its opposite side an extension *i*, provided with 70 recesses or seats *j*, and a ridge *k* between the recesses.

A spring-pressed pin *l* is carried by the cam member, said pin normally engaging one of the seats *j* of the lever member and 75 working longitudinally within a recess or seat *m* of a larger pin or projection 45^a of said member, said larger pin being one of the series of pins 45 and working within a slot 46 of the end collar 42^b, said pin 45^a 80 having an axial reduced extension to which the return finger 54 of the collar 42^b is connected.

The cam member carries a pawl *p*, intermediately pivoted at *p'* and provided with a 85 laterally extending tail end *q*, normally engaging the notch *b* of the fast member, to lock the cam member to the shaft, said pawl having an inwardly extending head end *q'*, 90 normally engaging the circumferential surface of the body of the lever member at the margin of the notch *h*.

In the reverse or counter-clockwise movement of the shaft, to rearrange the teeth or dogs of the collars to reverse spiral, the 95 line of collars being locked in their spiral arrangement to the shaft by the engagement of the tail end *q* of the pawl *p* with the notch *b* of the fast member, the head *g* of the lever member will be first brought 100 against a pivoted check *r*, carried by a bell-crank lever 59, forming part of the rocking means for the carrying shaft, to prevent further movement of the lever member with the shaft, the pin *l* of the cam member then 105 moving within the seat *j* of the lever member and allowing a movement of the cam member with respect to the lever member sufficient to cause the head *q'* of the pawl *p* to be brought opposite the lateral notch 110 *h* of the lever member, the pin then engaging the ridge *k* and resisting any further movement of the cam member with the shaft and with respect to the lever member, the fast member continuing to turn with 115 the shaft and, by engagement of the beveled wall of the notch *b* with the tail end *q* of the pawl *p*, pushing said tail end out of said notch and releasing the lock between the fast member *a* and the dog-carrying 120 cam member *c*, for holding the dogs or teeth of the collars in spiral relation.

The reverse movement of the shaft being continued, the fast end collar 42^a, all of the other collars 42 and the other end collar 125 42^b will turn with the shaft, the pin 45^a of the cam member being held from turning with the shaft, as previously stated. Therefore, this pin 45^a of the cam member will next arrive at the end of the slot 46 of the 130

collar 42^b, and will then check said collar 42^b from further movement with the shaft, said collar having moved a distance equal to the length of the slot 46.

- 5 The pin 45 of the collar 42^b being now checked, with said collar, from further rotation with the shaft, the second collar 42 in line will move with the shaft the length of the slot 46 thereof, when the end wall 10 of said slot will be brought against the pin 45 of the collar 42^b, to prevent further movement with the shaft of said second collar in line, said collar having moved with the shaft a distance equal to the combined 15 length of two slots 46. This step by step or successive checking of the collars will follow, in the reverse movement of the shaft, throughout the line of collars, to the fast collar 42^a, which will, when the spiral re- 20 arrangement is completed, have moved a distance equal to the sum of the length of all of the slots 46, the collar next adjacent thereto a distance equal to the sum of the length of all of the slots less the length of 25 one slot, etc.

The collar 42^a is made fast to the shaft by a pin *s* thereof, engaging a radial notch *s'* of an extra collar *t*, fast to the shaft.

- The spiral rearrangement of the dogs or 30 teeth of the collars being completed, the fast collar 42^a will exert a strain upon the line of collars, to rotate them all bodily with the shaft, this strain being sufficient to cause the spring-pressed pin *l* to ride 35 over the ridge *k* of the lever member, into engagement with the other seat *j* thereof, and in this movement of the cam member the lever member will be checked against further movement with the shaft by engagement of 40 the head *g* of its radial extension with the device *r*, thereby admitting of the engagement of the free end of the check *r* with a lateral notch *c'* of the cam member, said check being thereby thrown, by the beveled 45 end wall of said notch, to position at the opposite side of said cam member, ready to engage the opposite side of said head, upon clockwise rotation of the carrying shaft, said head normally barring the entry of the 50 check within said notch.

In the movement of the lever member to reverse the check device, the tail end *q* of the pawl of the cam member will again be brought opposite the notch *b*, and the head 55 end *q'* of the pawl will again ride upon the circumferential surface of the body *e'*, at the opposite margin of the lateral notch *h*, the cam member being thereby again locked to the fast member and the series of collars 60 being all positively locked in spiral relation.

In the clockwise movement of the operating handle, the same action takes place to check the movement of the pin 45 with the shaft 9 while rearrangement of the carrying teeth to reverse spiral is being accom-

plished; to release the lock holding the series of collars with the carrying teeth thereof in spiral relation, and to reengage said lock and at the same time to release the check upon the movement of the pin 45^a 70 with said shaft.

In the case of the Reissue Patent No. 13,841, dated December 8, 1914, a check spring is provided for the collar at one end, said spring acting to prevent the rotation 75 of the collar at one end until the rearrangement to reverse spiral is accomplished, and continuing to check the rotation of the carrying shaft after such rearrangement, and at all times, but in the present case, after the 80 rearrangement to reverse spiral and the locking of the series of collars, there is no check or brake upon the rotation of the carrying shaft.

I claim:

1. Carrying mechanism for calculating machines, including a rotary shaft bearing loose collars having movable teeth or dogs, said teeth spirally arranged entirely around the shaft in a single series, said collars 90 adapted for movement upon the shaft to rearrange the teeth thereof in a reverse spiral also extending entirely around the shaft.

2. Carrying mechanism for calculating machines, including a rotary shaft bearing 95 loose collars and a fast end collar, the collars having movable teeth or dogs spirally arranged entirely around the shaft in a single series and clutch connections adapted to allow a limited movement of the loose 100 collars with respect to each other and said end collar and being capable of rearrangement to adjust the teeth thereof into a reverse spiral also extending entirely around the shaft.

3. Carrying mechanism for calculating machines, including a rotary shaft bearing loose collars and a fast end collar, the collars having movable teeth or dogs spirally arranged around said shaft in a single series 110 and pin and slot connections adapted to allow a limited movement of the loose collars with respect to each other and to said end collar and capable of rearrangement to adjust the teeth thereof into a reverse spiral. 115

4. Carrying mechanism for calculating machines, including a rotary shaft bearing loose collars and a fast end collar, the collars having movable teeth or dogs spirally arranged around the shaft in a single series, 120 pin and slot connections adapted to allow a limited movement of the loose collars with respect to each other and said end collar and capable of rearrangement to adjust the teeth thereof into a reverse spiral, and 125 means for checking the movement of the other end collar while the rearrangement is being effected.

5. Carrying mechanism for calculating machines, including a rotary shaft bearing 130

loose collars and a fast end collar, the collars having movable teeth or dogs spirally arranged around the shaft in a single series and pin and slot connections adapted to allow a limited movement of the loose collars with respect to each other and to said end collar and being capable of rearrangement to adjust the teeth thereof into a reverse spiral, means for checking the movement of the other end collar while the rearrangement is being effected, reciprocatory carrying members adapted for operation by the registering wheels of the machine and for actuation of said teeth, spring means for returning the teeth to normal position, and means for returning said members to normal position comprising arms loose upon said shaft having connection with the pins of said collars and movable thereby to opposite sides of said teeth and adapted to return said members to normal position.

6. Carrying mechanism for calculating machines, including a rotary shaft bearing loose collars and a fast end collar, the collars having movable teeth or dogs spirally arranged around the shaft and clutch connections adapted to allow a limited movement of the loose collars with respect to each other and said end collar, and means operable upon rotation of said shaft for checking the movement of the other end collar with the shaft, said means releasable upon rearrangement of the collars with the teeth thereof in reverse spiral.

35 7. Carrying mechanism for calculating machines, including a rotary shaft bearing loose collars and a fast end collar, the collars having movable teeth or dogs spirally arranged around the shaft and clutch connections adapted to allow a limited movement of the loose collars with respect to each other and said end collar, and means operable upon reverse rotation of the shaft for checking the movement of the other end collar with the shaft, said check releasable upon rearrangement of the collars with the teeth thereof in reverse spiral and afterward releasing the collar, embodying means for positively locking the series of collars with their teeth in spiral relation.

8. Carrying mechanism for calculating machines, including a rotary shaft bearing loose collars and a fast end collar, the collars having movable teeth or dogs spirally arranged around the shaft and clutch connections adapted to allow a limited movement of the loose collars with respect to each

other and said end collar, and means operable upon reverse rotation of said shaft in either direction for checking the movement of the other end collar with the shaft, said check releasable upon rearrangement of the collars with the teeth thereof in reverse spiral and embodying means for positively locking the series of collars with their teeth in spiral relation, said lock releasable previous to such rearrangement.

9. Carrying mechanism for calculating machines, including a rotary shaft bearing loose collars and a fast end collar, the collars having movable teeth or dogs spirally arranged around the shaft and pin and slot connections adapted to allow a limited movement of the loose collars with respect to each other and to said end collar, and means operable upon reverse rotation of the shaft in either direction, and including a reversible stop device, for checking the movement of the other end collar, said stop device releasable upon rearrangement of the collars with their teeth in reverse spiral, embodying means for positively locking the series of collars with their teeth spirally arranged and for reversing the stop device, said lock releasable previous to such rearrangement.

10. Carrying mechanism for calculating machines, including a rotary shaft bearing loose collars and a fast end collar, the collars having pin and slot connections adapted to allow a limited movement of the loose collars with respect to each other and said end collar and movable teeth or dogs spirally arranged around the shaft, a member fast upon the shaft, the loose end collar having releasable means engaging said fast member to lock the collars with their teeth in spiral relation, a member loose upon the shaft and a reversible stop device co-operating with said loose end collar and said fast member and operable upon reverse rotation of the shaft in either direction to check the movement of the loose end collar with the shaft to relock the collars after the release thereof and the rearrangement of the teeth in reverse spiral, and to reverse the stop device.

In testimony whereof I affix my signature in presence of two witnesses.
